(57) **CLAIM**

The ornamental design for a structure for mobility station as shown and described.

DESCRIPTION

1. Structure for mobility station

1.1 : Perspective

1.2 : Front

1.3 : Back

1.4 : Right

1.5 : Left

1.6 : Top

1.7 : Bottom

1.8 : Reference view

1.9 : Reference view

1.10 : Reference view

1.11 : Reference view

1.1 is a top, front and left perspective view of a structure for mobility station showing our new design; 1.2 is a front elevation view thereof; 1.3 is a rear elevation view thereof; 1.4 is a right side elevation view thereof; 1.5 is a left side elevation view thereof; 1.6 is a top plan view thereof; 1.7 is

(Continued)

a bottom plan view thereof; **1.8** to **1.11** are reference views thereof showing how this article is used; the parts shown by means of broken lines in reproductions **1.9** to **1.11** are not part of the claimed design; and the reflections/shadows shown in reproductions **1.1** to **1.11** are disclaimed; minor variations in color are due to different lighting conditions.
